WELL SCREEN PERFORATION CLEANER

Bryant P. Arterbury and George M. Clark, Houston, Tex., assignors of thirty-three and one-third percent to Roy L. Arterbury, Houston, Tex.

Application October 20, 1955, Serial No. 541,570

5 Claims. (Cl. 166—177)

This invention relates to tools as oil well service tools termed well screen perforation cleaners. Specifically, it relates to a tool which may be used to clean the screen or perforated section of tubing which is interposed in the well casing in the region of the oil producing formation, this application being a continuation-in-part of co-pending patent application Serial Number 344,592, for Cleaning Tool, filed in the United States Patent Office by Bryant P. Arterbury and George M. Clark under filing date of March 25, 1953 and issued April 3, 1956, as Patent No. 2,740,481.

It is an important object of this invention to provide a cleaning tool of this class having a packer assembly which may be used with a pipe or tubing string lowered into a cased well bore having a perforated casing, the tubing passing sealably through the casing at the top of the well where means is provided to pump fluid into the casing below the seal to thereby pressurize and clean the perforations and adjacent formation as the packer assembly is manipulated to correlate the application of the pressurized fluid.

It is also an important object of this invention to employ such packer assembly on a tubing string in such a cased well bore as hereinabove described in a manner to test the pressure the casing will withstand above the perforated section.

It is another and primary object of this invention to provide a packer assembly of the class described operable on a tubing string extending sealably through a lower perforated cased well bore into which pressurized fluid is introduced at the top below the seal to pressurize and also clean the perforations and adjacent formation through manipulation of the packer assembly.

It is also another primary object of this invention to provide a packer assembly of the class described operable on a tubing string in such a cased well bore in a manner to test the pressure the unperforated casing will withstand above the perforated lower portion.

It is yet another primary object of this invention to provide a packer assembly of the class described which is versatile of operation in such a well bore, and which is capable of operative adjustment, as by rotation.

Other and further objects of this invention will be apparent when the specification is considered in connection with the drawings in which:

Fig. 1 is a sectional elevation showing an embodiment of the invention as it is lowered on a pipe string into a well bore; and

Fig. 2 is a sectional elevation of the embodiment of Fig. 1 shown in position in the well bore and operative to clean a perforated section of casing.

Referring in detail to the drawings, a mandrel body 11 is shown connected to a pipe or tubing string 42 which extends within a cased well bore 40 to the top of the well. A closure 41 at the top of the casing 40 sealably encloses the tubing 42, as by the provision of O-rings 51 in the closure, and the tubing 42 extends above the

closure to deliver fluid upwardly to conventional receiving means therefor.

The mandrel body 11' has a packer assembly 26' slidably thereon below a shoulder 55 on the mandrel body 11'. Such assembly includes a sleeve 27' as the element providing this sliding contact. The lower part of the sleeve 27' provides an internal recess space 57 therein and radial ports 28 through the mandrel wall communicate with such recess. A retaining nut 31 is threaded onto the lower end of the sleeve 27' and provides the retaining seat for a cup-type packer 29 which extends thereabove surrounding the sleeve 27' and in slightly spaced relation from the ports 28 thereon. Such sleeve 27' has longitudinal slots 44 therein and pins 45 extend across such slots at the upper and lower ends thereof to be supported in the walls defining such slots. Friction springs 43 have their ends connected to such pins 45 and are of a configuration to bear outwardly with substantial frictional engagement against the wall of the casing 40.

The retaining nut 31 is countersunk at its lower end to provide a valve seating surface or valve seat 59, and in the lowermost position of the packer assembly 26', such valve seat 59 seats against an inclined shoulder 32 provided by a mandrel part or valve element 56 of larger outer diameter than is the mandrel diameter immediately thereabove. A circumferential series of longitudinal ports 33 is provided in the part 56 to extend to the face of the shoulder 34, and when the nut 31 seats on the shoulder 32 fluid communication may be established from the annular space surrounding the mandrel 11' above the packer 29, through the ports 28, the space 57, and the longitudinal ports 33, to the space surrounding the mandrel 11' below the packer 29. An annular relief valve 35 which slides on a turned down mandrel part 58 below the mandrel 56 is externally threaded to receive an adjustment nut 37 thereon, and a spring 36 bears downwardly on the upper face of the adjustment nut 37 and upwardly against the under face of the relief valve 35 to bias the valve 35 normally to close the ports 33. A shoe 38 is threaded onto the end of the mandrel part 38 to guide the tool into the well and to protect the external threads on the part 58. As indicated diagrammatically in the drawings, conventional friction elements 46 are provided on the adjustment nut 37 to bear frictionally against the wall of the casing 40. A pin 51 in the mandrel body 11' within the sleeve 27' extends through a well known J slot 51 shown in the sleeve 27' to effect positionings to be hereinafter described.

As shown in Fig. 1 the sleeve 27' is maintained in the relative vertical position shown with relation to the mandrel body 11' as the tool is lowered into the well bore by virtue of the frictional drag of the springs 43 maintaining the sleeve 27' in abutment at its top with the mandrel body. In such position right handed or clockwise rotation of the mandrel body 11' with relation to the sleeve 27' as viewed from the top of the well, while the sleeve 27' is inhibited against rotation by the frictional engagement of the springs 43 with the casing 40, will result in the pin 51 in the mandrel body 11' moving to the end of the lower leg of the J-slot 52 after which the sleeve 27' and mandrel body 11' descend together in locked relation, or may be rotated together in right hand or clockwise direction as viewed from the top of the well.

In this position the operation of the pump 47 at the top of the well to deliver fluid through the pump discharge 48 and down the casing 40 results in fluid being pumped into the interior of the cup-like packer 29 and through the ports 28 and downwardly through the space between mandrel body 11' and sleeve 27' to pass down to the bottom of the tool and then upwardly through the

mandrel bore 13 to carry along therewith any sand which may have entered the casing 40 through perforations 53 therein, as from a sand formation 54.

This operation can be carried out as the tool is lowered or moved vertically since the packer 29 is not set by the pumping of fluid through the interior thereof, and in this vertical movement the packer 29 may or may not frictionally engage the casing 40, dependent in part upon the force with which the fluid is pumped. Thus the casing 40 may be washed at selective vertical positions.

When the tool reaches a vertical position where it may be desired to wash extensively and also to wash the perforations 53 and the sand 54 externally of the casing 40, the mandrel body 11' is rotated in a counter-clockwise or left handed direction as viewed from the top of the well, and as the springs 43 frictionally engage the casing 40 and are inhibited against rotation, the pin 51 is moved to the bottom of the upper or vertical leg of the J-slot. Then the mandrel body 11' may be lifted with relation to the sleeve 27' as the springs 43 frictionally engage the casing 40 to inhibit upward movement of the sleeve 27'. See Fig. 2.

Now, as fluid is pumped down the casing 40 with the valve seat 59 of the retaining nut 31 seated on the inclined shoulder 32 of the valve element 56, the packer 29 is set against the casing 40 by virtue of the fluid pressure exerted within the cup of the packer, since fluid can only pass through the packer if at a pressure to pass down the longitudinal ports 33 and radially outwardly past the shoulder 34 against the pressure of the upwardly urged valve member 35. When the pressure of the pumped fluid is built up to this degree, such pressure is ample to firmly set the packer 29 against the casing 40. Such pressure of the pumped fluid is also adequate to wash through the perforations 53 above the packer into the sand formation 54 and downwardly therethrough to return to the casing 40 through perforations 53 below the packer 29, and to carry the washed sand downwardly in the casing and thence upwardly through the mandrel bore 13 to the top of the well bore for disposition above the closure 41.

The nut 37 has thereon friction elements or scratchers 46 for the purpose of scraping and cleaning the casing 40 and also these friction elements 46 bind the nut against rotation while the tool may be rotated, with the consequence that the nut 37 may be raised or lowered on the mandrel 11', dependent upon the direction of tool rotation, to thereby increase or decrease the tension of the spring 36 and thereby increase or decrease the fluid pressure required to open the valve member 35.

In lifting the tool from the position of Fig. 1, the pin 51 on the mandrel 11' is lifted into the small vertical slot thereabove forming the lower tip of the J, and then the mandrel 11' and sleeve 27' are locked together against relative rotation therebetween, and in a like manner with the pin 51 in the vertical slot of the J-slot 52, as shown in Fig. 2, the mandrel 11' and sleeve 27' are locked together against relative rotation.

Broadly this invention relates to a cleaning tool operable on a tubing string in a manner that fluid circulated down the casing will set the packer thereon so that the pressurized fluid may then be circulated to clean the perforated casing and wash the formation outwardly thereof. The invention is not limited to the structures disclosed and described but other structures are considered as well as such may fall within the broad spirit of the invention and within the broad scope of interpretation claimed and merited for the appended claims.

What is claimed is:

1. A well screen perforation cleaner for cleaning a perforated section of a cased well bore and adapted at its upper end for connection to a pipe stem to be lowered thereon into a well, said cleaner including a hollow mandrel connected to said stem as the lowermost element thereof, a sleeve encircling and slidable upon said man-

drel, means carried by said sleeve and connected thereto for yieldably, frictionally engaging said casing to inhibit movement of said sleeve, an upwardly facing cup-like packer encircling said sleeve and carried thereby to frictionally engage the well bore wall, a fluid passage provided in said sleeve extending from its exterior above the connection of said packer thereto through its interior to discharge therefrom below said connection, a valve seat on the exterior of the lower end of said sleeve outwardly of said fluid passage, a valve element carried by

5 said mandrel and engageable with said valve seat and encircling said mandrel beneath said packer and said sleeve and having a flow passage therethrough establishing fluid communication with said fluid passage when said 10 valve element is in seated engagement with said valve seat, means biased to normally close the lower end of said valve element flow passage, said mandrel being adapted to be lifted with relation to said sleeve to seat said valve element on said valve seat to place said fluid passage and said flow passage in communication and said packer then being expandable into firm engagement with the well bore wall by pressure of fluid from thereabove and said biased means then being openable by excessive fluid pressure.

2. A well screen perforation cleaner for cleaning a perforated section of a cased well bore and adapted at its upper end for connection to a pipe stem to be lowered thereon into a well, said cleaner including a hollow mandrel connected to said stem as the lowermost element thereof, a sleeve encircling and slidable upon said mandrel, means carried by said sleeve and connected thereto for yieldably, frictionally engaging said casing to inhibit movement of said sleeve, an upwardly facing cup-like packer encircling said sleeve and carried thereby to

30 frictionally engage the well bore wall, a fluid passage provided in said sleeve extending from its exterior above the connection of said packer thereto through its interior to discharge therefrom below said connection, a valve seat on the exterior of the lower end of said sleeve outwardly of said fluid passage, a valve element carried by said mandrel and engageable with said valve seat and encircling said mandrel beneath said packer and said sleeve and having a flow passage therethrough establishing fluid communication with said fluid passage when said 35 valve element is in seated engagement with said valve seat, means biased to normally close the lower end of said valve element flow passage, said mandrel being adapted to be lifted with relation to said sleeve to seat said valve element on said valve seat to place said fluid passage and said flow passage in communication and said packer then being expandable into firm engagement with the well bore wall by pressure of fluid from thereabove and said biased means then being openable by excessive fluid pressure.

3. A well screen perforation cleaner for cleaning a perforated section of a cased well bore and adapted at its upper end for connection to a pipe stem to be lowered thereon into a well, said cleaner including a hollow mandrel connected to said stem as the lowermost element thereof, a sleeve encircling and slidable upon said mandrel, means carried by said sleeve and connected thereto for yieldably, frictionally engaging said casing to inhibit movement of said sleeve, an upwardly facing cup-like packer encircling said sleeve and carried thereby to

40 frictionally engage the well bore wall, a fluid passage provided in said sleeve extending from its exterior above the connection of said packer thereto through its interior to discharge therefrom below said connection, a valve seat on the exterior of the lower end of said sleeve outwardly of said fluid passage, a valve element carried by said mandrel and engageable with said valve seat and encircling said mandrel beneath said packer and said sleeve and having a flow passage therethrough establishing fluid communication with said fluid passage when said 45 valve element is in seated engagement with said valve seat, means biased to normally close the lower end of said valve element flow passage, a nut threaded on the exterior of said mandrel and a spring reacting between said nut and said biased means as the means normally biasing said biased means to closed position, said mandrel being adapted to be lifted with relation to said sleeve to seat said valve element on said valve seat to place said fluid passage and said flow passage in communication and said packer then being expandable into firm engagement with the well bore wall by pressure of fluid from thereabove and said biased means then being openable by excessive fluid pressure.

4. A well screen perforation cleaner for cleaning a perforated section of a cased well bore and adapted at its upper end for connection to a pipe stem to be lowered thereon into a well, said cleaner including a hollow mandrel connected to said stem as the lowermost element thereof, a sleeve encircling and slidable upon said mandrel, means carried by said sleeve and connected thereto for yieldably, frictionally engaging said casing to inhibit movement of said sleeve, an upwardly facing cup-like packer encircling said sleeve and carried thereby to

50 frictionally engage the well bore wall, a fluid passage provided in said sleeve extending from its exterior above the connection of said packer thereto through its interior to discharge therefrom below said connection, a valve seat on the exterior of the lower end of said sleeve outwardly of said fluid passage, a valve element carried by said mandrel and engageable with said valve seat and encircling said mandrel beneath said packer and said

55 sleeve and having a flow passage therethrough establishing fluid communication with said fluid passage when said valve element is in seated engagement with said valve seat, means biased to normally close the lower end of said valve element flow passage, a nut threaded on the exterior of said mandrel and a spring reacting between said nut and said biased means as the means normally biasing said biased means to closed position, said mandrel being adapted to be lifted with relation to said sleeve to seat said valve element on said valve seat to place said fluid passage and said flow passage in communication and said packer then being expandable into firm engagement with the well bore wall by pressure of fluid from thereabove and said biased means then being openable by excessive fluid pressure.

60 3. A well screen perforation cleaner for cleaning a perforated section of a cased well bore and adapted at its upper end for connection to a pipe stem to be lowered thereon into a well, said cleaner including a hollow mandrel connected to said stem as the lowermost element thereof, a sleeve encircling and slidable upon said mandrel, means carried by said sleeve and connected thereto for yieldably, frictionally engaging said casing to inhibit movement of said sleeve, an upwardly facing cup-like packer encircling said sleeve and carried thereby to

65 frictionally engage the well bore wall, a fluid passage provided in said sleeve extending from its exterior above the connection of said packer thereto through its interior to discharge therefrom below said connection, a valve seat on the exterior of the lower end of said sleeve outwardly of said fluid passage, a valve element carried by said mandrel and engageable with said valve seat and encircling said mandrel beneath said packer and said

sleeve and having a flow passage therethrough establishing fluid communication with said fluid passage when said valve element is in seated engagement with said valve seat, means biased to normally close the lower end of said valve element flow passage, a nut threaded on the exterior of said mandrel and a spring reacting between said nut and said biased means as the means normally biasing said biased means to closed position, said mandrel being adapted to be lifted with relation to said sleeve to seat said valve element on said valve seat to place said fluid passage and said flow passage in communication and said packer then being expandable into firm engagement with the well bore wall by pressure of fluid from thereabove and said biased means then being openable by excessive fluid pressure, said nut having friction means thereon engaging said casing whereby with said drill stem being connected to said pipe stem rotation of said pipe stem in one direction may move said nut upwardly to tighten spring reaction against said biased means or whereby rotation of said pipe stem in the reverse direction may move said spring downwardly to decrease spring reaction against said biased means.

4. A well screen perforation cleaner for cleaning a perforated section of a cased well bore and adapted at its upper end for connection to a pipe stem to be lowered thereon into a well, said cleaner including a hollow mandrel connected to said stem as the lowermost element thereof, a sleeve encircling and slidably upon said mandrel, means carried by said sleeve and connected thereto for yieldably, frictionally engaging said casing to inhibit movement of said sleeve, an upwardly facing cup-like packer encircling said sleeve and carried thereby to frictionally engage the well bore wall, a fluid passage provided in said sleeve extending from its exterior above the connection of said packer thereto through its interior to discharge therefrom below said connection, a valve seat on the exterior of the lower end of said sleeve outwardly of said fluid passage, a valve element carried by said mandrel and engageable with said valve seat and encircling said mandrel beneath said packer and said sleeve and having a flow passage therethrough establishing fluid communication with said fluid passage when said valve element is in seated engagement with said valve seat, means biased to normally close the lower end of said valve element flow passage, said sleeve and said mandrel providing cooperating J-slot and pin means whereby said sleeve and said mandrel may be locked together or said mandrel may be lifted with relation to said sleeve to bring said valve element into seated engagement with said valve seat, said mandrel being adapted to be lifted with relation to said sleeve to seat said valve element on said valve seat to place said fluid passage and said flow passage in communication and said packer then being expandable in-

to firm engagement with the well bore wall by pressure of fluid from thereabove and said biased means then being openable by excessive fluid pressure.

5. A well screen perforation cleaner for cleaning a perforated section of a cased well bore and adapted at its upper end for connection to a pipe stem to be lowered thereon into a well, said cleaner including a hollow mandrel connected to said stem as the lowermost element thereof, a sleeve encircling and slidably upon said mandrel, means carried by said sleeve and connected thereto for yieldably, frictionally engaging said casing to inhibit movement of said sleeve, an upwardly facing cup-like packer encircling said sleeve and carried thereby to frictionally engage the well bore wall, a fluid passage provided in said sleeve extending from its exterior above the connection of said packer thereto through its interior to discharge therefrom below said connection, a valve seat on the exterior of the lower end of said sleeve outwardly of said fluid passage, a valve element carried by said mandrel and engageable with said valve seat and encircling said mandrel beneath said packer and said sleeve and having a flow passage therethrough establishing fluid communication with said fluid passage when said valve element is in seated engagement with said valve seat, means biased to normally close the lower end of said valve element flow passage, said sleeve providing a J-shaped slot therein and said mandrel providing a pin to extend into said slot whereby said mandrel and said sleeve are locked together against relative rotation with said pin in the top of the shorter, vertically extending leg of said J-shaped slot and with said valve seat spaced above said valve element or whereby with said pin positioned in the longer, vertically extending leg of said J-shaped slot said mandrel may be lifted with relation to said sleeve to bring said valve element into seated engagement with said valve seat with said pin in the top of said longer, vertically extending slot and with said mandrel and said sleeve locked together against relative rotation therebetween, said mandrel being adapted to be lifted with relation to said sleeve to seat said valve element on said valve seat to place said fluid passage and said flow passage in communication and said packer then being expandable into firm engagement with the well bore wall by pressure of fluid from thereabove and said biased means then being openable by excessive fluid pressure.
